(57) **CLAIM**

The ornamental design for a sensor housing, as shown and described.

DESCRIPTION

FIG. 1 is a top perspective view of a sensor housing showing the new design.

FIG. 2 is a bottom perspective view of the sensor housing showing the new design.

FIG. 3 is a top down view of the sensor housing showing the new design.

FIG. 4 is a bottom up view of the sensor housing showing the new design.

FIG. 5 is a right side view of the sensor housing showing the new design.

FIG. 6 is a left side view of the sensor housing showing the new design.

FIG. 7 is a front view of the sensor housing showing the new design; and,

FIG. 8 is a back view of the sensor housing showing the new design.

Within the drawings, the dashed lines and the areas within the dashed lines show unclaimed portions of the sensor housing, and form no part of the claimed design.

1 Claim, 4 Drawing Sheets
